(57) **CLAIM**

We claim the ornamental design for a display area and key array for a handset, as shown and described.

DESCRIPTION

FIG. 1 is a front view of the display area and key array for a handset;

FIG. 2 is a top plan view thereof; and,

FIG. 3 is a perspective front view thereof.

The broken line showings throughout the drawing views are for illustrative purposes only and form no part of the claimed design.
